UNITED STATES PATENT OFFICE.

JOSEPH W. BISHOP AND BYRON C. BOOTH, OF MUSKEGON, MICHIGAN, ASSIGNEES TO THE BRUNSWICK-BALKE-COLLENDER COMPANY, OF WILMINGTON, DELAWARE, A CORPORATION OF DELAWARE.

COMBINED PHONOGRAPH AND RADIO APPARATUS.

Application filed June 30, 1924. Serial No. 723,104.

This invention relates to a combined phonograph and radio apparatus and may be embodied in a cabinet such as disclosed in the application of Martin Nystrom, Serial No. 5 713,128, filed May 14, 1924, or in any other suitable cabinet.

The primary object of our invention is to provide a combination phonograph and radio apparatus in which either the phonograph or 10 the radio apparatus may be used, selectively.

Another object is to provide a combined phonograph and radio apparatus in which the amplifying horn normally used with the phonograph may be used at will as the amplifying horn for the radio apparatus. 15

More specifically, the object of our invention is to provide a valve operable from the outside of the cabinet to connect the amplifying horn with the tone arm of the phonograph or with the loud speaker of the radio apparatus, at will.

In the accompanying drawings in which we have shown an embodiment of our invention,

Fig. 1 is a front elevation of a cabinet embodying our invention.

Fig. 2 is a vertical section through Fig. 1.

Fig. 3 is a section on the line 3—3 of Fig. 2, and

Fig. 4 is a section on the line 4—4 of Fig. 2.

Referring now to the drawings, 1 designates a suitable cabinet containing a phonograph designated generally at 2, and a radio apparatus designated generally at 3. The phonograph comprises the usual turn-table 4, reproducer 5, tone-arm 6, and amplifying horn 7. The bell portion of the amplifying horn is received in a block 8, extending through which is a passage 9. Connected to the other end of the block 8 is the neck 10 to connect the block with the tone-arm 6. As is well-known in the art, the sound waves pass through the tone-arm 6, neck 10 and block 8 to the amplifying horn 7.

We provide the neck 10 with an enlarged portion 11 horizontally disposed and forming a seat for a sliding valve 12 and also providing a seat 13 for the reception of the tubular arm 14 connected to the loud speaker 15 of the radio apparatus.

The valve 12 is provided with an opening 16 therein adapted to form a continuous passageway with the tone-arm 6 and the neck 10. The valve 12 is further provided with a curved opening 17 having one end adapted

to register with and form a smooth continuation of the neck 10, and the other end of which is adapted to register with and form a smooth continuation of the arm 14. 5

The valve 12 as plainly shown in Figs. 2 and 4 is slidably mounted in the enlarged portion 11 of the neck 10 and it is adapted to be slid therein so that the opening 16 may be brought in alignment with the opening in the neck 10 and in the tone-arm 6, or the opening 17 may be brought into alignment with the 10 openings in the neck 10 and in the arm 14. It will be understood, of course, that the loud speaker 15 is connected to the radio apparatus 3 by any suitable means. The upper part of the neck 10 is connected to the motor-board 18 and the valve 12 is adapted to be operated from the outside of the cabinet by means of a push rod 19 connected thereto and extending through one wall 20 of the cabinet, being provided externally of the cabinet with a 15 suitable handle 21. Suitable means may be provided to limit motion of the valve to insure that the openings 16 and 17 respectively are brought to the correct positions in registry with the neck 10. This means may consist of 20 a pin 12' on the valve 12 and engaging a slot 11' in the neck 11. The valve serves as a means to modify the tone of the reproduction from either the phonograph or the loud speaker, this result being achieved, of course, 25 by sliding the valve to increase or decrease the size of opening through which the sound may pass into the neck 10.

From the above description it will be apparent that we have devised a phonograph and radio apparatus in which the same amplifying horn may be employed, with either the phonograph or the radio apparatus, by means of a simple adjustment from the outside of the cabinet in which the apparatus is 30 contained, and that the same means may be employed to modify the tone of the reproduction in a very simple and efficient manner. 35

We are aware that changes in the form, construction and arrangement of parts may 40 be made without departing from the spirit and without sacrificing the advantages of the invention and we reserve the right to make all such changes as fairly fall within the scope of the following claims. 45

We claim:

1. In a device of the character described, an oscillatory tone-arm, a fixed amplifying

- horn, a neck connecting said tone-arm to said amplifying horn, a radio loud speaker connected to said neck, a one piece valve slidable in said neck and having passageways to operatively connect said horn with either said tone-arm or said loud speaker, and means for limiting the movement of said valve, said means comprising a pin on said valve engaging a slot in said neck.
- 10 2. In a device of the character described, an amplifying horn, a phonograph reproducer, an arm, a radio loud speaker connected to the arm, a neck interposed between the horn, the reproducer and the arm, a horizontally disposed valve seat in the neck, a one-piece valve slidably disposed in said seat and having independent passageways to connect the reproducer or the loud speaker with the horn, means for adjusting the valve, and means arranged on said valve and en-
- gaging said neck for limiting the movement of the valve.
- 15 3. In a device of the character described, a neck having a horizontally disposed valve seat therein, an amplifying horn connected to the bottom of the neck, a phonograph reproducer connected to the top of the neck, an arm connected to the side of the neck, a radio loud speaker connected to the outer end of the arm, a one-piece valve slidable in said seat and having a straight vertical passage to connect the reproducer with the horn and an independent angle passage to connect the loud speaker with the horn, means for adjusting the valve, a pin on said valve and engaging a slot in said neck for limiting the movement of the valve.
